INSULATING COLUMN STRUCTURE

Joseph L. McKibben, Los Alamos, N. Mex., assignor to the United States of America as represented by the United States Atomic Energy Commission

Application October 8, 1948, Serial No. 53,401

5 Claims. (Cl. 250—27.5)

1

The present invention relates to high voltage apparatus and, more particularly, to insulating structures employed to separate bodies at widely different potentials in such apparatus.

In many applications of high voltage apparatus or systems, it has been found that the overall effectiveness is limited by the resistance of the insulating structures to spark over or discharge breakdown. Many attempts to maximize this resistance to breakdown for well known insulating materials such as glass, porcelain or the like, have been described in the literature and are well known. For example, it has been found that structures comprising a plurality of non-conducting sections separated by metallic shims or the like have been able to withstand higher potential differences than a solid or laminated structure of the same insulating material not separated by the equipotential shims. Such a structure is described in the U. S. patent to Machlett et al., No. 2,376,439 issued May 22, 1945.

While such laminar structures have been found somewhat effective in normal high voltage applications, in apparatus in which the potential difference between operating electrodes is of the order of many hundreds of kilovolts, cold emitted electrons following the electric field have led to breakdown and flashover. Thus, while the insertion of equipotential shims or devices serving a similar purpose between sections of insulating material have been found to equalize the potential stress applied to the insulating material, they have not prevented cold emission induced breakdown and in fact have contributed to such breakdown to some extent in the voltage range being considered. Furthermore, the elongation of surface creepage paths as disclosed by Trump in U. S. Patent 2,182,185 does not avoid the breakdown induced by cold emitted electrons in the same range.

It is thus seen to be an object of the present invention to provide improved high voltage apparatus capable of operating at maximized potential difference between the principal electrodes while minimizing the spatial separation of said electrodes.

It is a further and more specific object of the present invention to provide an insulating structure for separating bodies operating at high potential differences which is extremely simple to construct.

Another object of the present invention is to provide an insulating structure which minimizes breakdown or flashover due to cold emission of electrons by the materials employed in the structure.

Other objects and advantages will be apparent to one skilled in the art from the following description when taken in connection with the drawings made part of this specification.

2

In the drawings:

Figure 1 is a longitudinal sectional view of high voltage apparatus embodying one form of the invention.

Figure 2 is a similar section in enlarged view of a portion of the apparatus shown in Figure 1 and providing details of the insulating structure.

Referring now to the drawings, the apparatus shown in Figure 1 is seen to comprise an elongated tubular envelope 10 of suitable insulating material such as a glass composition, a pair of operating electrodes 11 and 12 supported in spaced relationship by end pieces 13 and 14 respectively and a source of direct current potential 15 associated with said electrodes and adapted to apply a direct current potential of the order of twelve to fifteen million volts between the same. The entire envelope 10 is hermetically sealed and adapted to withstand an external pressure of upward of 150 p. s. i. and to be internally evacuated, for example, to the extent that the residual pressure is approximately of the order of 10^{-5} millimeters of mercury or less.

Electrode 11 is adapted to permit the introduction into the evacuated tube of ions of a predetermined type, for example, deuterons, the type of source and manner of introduction being indicated schematically and generically referred to by numeral 16 as the details thereof are well known in the art and form no part of the present invention.

Electrode 12, on the other hand, is adapted to act as a target for the ions introduced at electrode 11 and accelerated in a beam by the twelve million volt potential difference established between said electrodes 11 and 12.

Now in such a device, if principles heretofore known were followed, the spatial separation of electrodes 11 and 12 would be great and dispersion of the charged particle beam would occur necessitating the introduction of a plurality of focussing electrodes and otherwise complicating the structure. In the present apparatus, it is possible to separate the electrodes by less than twelve feet, the insulating structure of envelope 10 being capable of operating under a potential difference of over 1,000,000 volts per foot.

The details of envelope 10 of the insulating structure are shown in Figure 2. It is seen to be constructed of a plurality of annular rings 20 of insulating material, separated by conducting annular shims 21. Rings 20 have parallel flat or plane faces which are perpendicular to the axis thereof. Sealing is accomplished by the application to adjacent plane faces of the shims 21 and rings 20 of a suitable cementitious material such as, for example, a vinyl plastic composition or the like. It has been found highly desirable in cementing the structural parts together to carefully clean the resulting joints and the surrounding materials with suitable solvents.

It is a feature of the present invention that the annular sections 20 are provided with a taper in the internal bore thereof, the direction of the taper being such that the diameter of the bore at the more positive plane surface (indicated by the plus sign) is larger than the diameter of the bore at the less positive plane surface (indicated by the minus sign).

It is immediately apparent that the cold emission of electrons under the influence of the intense electric field which exists in the axial direction is substantially ineffective to cause breakdown or flashover of the insulating material. More particularly, if cold emitted electrons are emitted at point A they follow the direction of the electric field i. e., a path perpendicular to the plane surface of the ring 20 are parallel to the longitudinal axis, and are thus led away from the said insulating material and cannot bombard the same to ultimately cause electrical breakdown thereof.

The taper is preferably uniform and about fifteen degrees to the axis, the exact taper being governed to some extent by the insulating material employed. The taper should be at least such as to prevent the said cold emitted electrons from following a path which leads to any portion of ring 20, thus indicating that it is not the increased creepage path afforded by the taper, but rather the interrelation of the electric field direction and the insulating material surface which leads to the desirable results herein disclosed.

It is thus seen that what has been described herein, for the purpose of illustration, is a single embodiment through which the principles of the invention may be carried out. While the inner bore of the insulating material section in the embodiment described is preferably uniformly tapered, in other applications the taper may well vary, the essential principle being that cold emitted electrons are prevented by the angular relation between the surface of the bore and the electric field, from returning to the said surface.

Likewise, it is apparent that many other variations in structure and materials will suggest themselves to one skilled in the art, however, such variations should be deemed to fall within the scope of the invention as it is defined with particularity in the appended claims.

What is claimed is:

1. The combination with at least one pair of operating electrodes, a source of direct current potential and means for connecting said source to said electrodes to establish a high potential and an electric field therebetween of an insulating structure for supporting said electrodes in fixed spaced relationship, comprising a plurality of annular sections of insulating material disposed in axial alignment, annular conducting shims separating said insulating material sections and coaxial therewith, said shims having their plane faces sealed to adjacent plane faces of said insulating material, the inner bore of said insulating material sections being tapered in a direction that when said bore is in substantial axial alignment with said electric field, the diameter of said bore at the more positive plane surface of said annular sections is larger than the diameter of said bore at the less positive plane surface of said sections.

2. A tubular insulating structure which comprises a plurality of annular sections of insulating material axially aligned and separated by an-

nular conducting shims, the inner bore of said insulating material sections being tapered in such a manner that when said sections are disposed in substantial axial alignment with an electrical field, the diameter of said bore at the more positive face of each of said sections is greater than the diameter of said bore at the less positive face of the same section.

3. A tubular insulating structure which comprises a plurality of annular sections of insulating material said sections having parallel plane faces and being axially aligned and separated by annular conducting shims, the inner bore of said insulating material sections being uniformly tapered in such a manner that when said sections are disposed in substantial axial alignment with an electrical field, the diameter of said bore at the more positive face of each of said sections is greater than the diameter of said bore at the less positive face of the same section.

4. An insulating envelope for supporting at least two bodies at a high potential difference is spaced relationship comprising a pair of closure sections each adapted to support at least one of said bodies, a plurality of plane faced annular insulating sections disposed between said closure sections, said insulating sections being axially aligned and separated by conducting material shims, said shims having their plane faces sealed to adjacent faces of said insulating sections and said closure sections being sealed to the insulating sections adjacent thereto, at least the inner bore of each of said insulating sections being tapered in such a manner that when said sections are disposed in substantial axial alignment with an electrical field, the diameter of said bore at the more positive face of each of said sections is greater than the diameter of said bore at the less positive face of the same section.

5. An insulating envelope for supporting at least two bodies at a high potential difference in spaced relationship comprising a pair of closure sections each adapted to support at least one of said bodies, a plurality of plane faced annular insulating sections disposed between said closure sections, said insulating sections being axially aligned and separated by conducting material shims, said shims having their plane faces sealed to adjacent faces of said insulating sections and said closure sections being sealed to the insulating sections adjacent thereto, at least the inner bore of each of said insulating sections being tapered in such a manner that when said sections are disposed in substantial axial alignment with an electrical field, the diameter of said bore at the more positive face of each of said sections is greater than the diameter of said bore at the less positive face of the same section.

6. An insulating envelope for supporting at least two bodies at a high potential difference in spaced relationship comprising a pair of closure sections each adapted to support at least one of said bodies, a plurality of plane faced annular insulating sections disposed between said closure sections, said insulating sections being axially aligned and separated by conducting material shims, said shims having their plane faces sealed to adjacent faces of said insulating sections and said closure sections being sealed to the insulating sections adjacent thereto, at least the inner bore of each of said insulating sections being tapered in such a manner that when said sections are disposed in substantial axial alignment with an electrical field, the diameter of said bore at the more positive face of each of said sections is greater than the diameter of said bore at the less positive face of the same section.

7. An insulating envelope for supporting at least two bodies at a high potential difference in spaced relationship comprising a pair of closure sections each adapted to support at least one of said bodies, a plurality of plane faced annular insulating sections disposed between said closure sections, said insulating sections being axially aligned and separated by conducting material shims, said shims having their plane faces sealed to adjacent faces of said insulating sections and said closure sections being sealed to the insulating sections adjacent thereto, at least the inner bore of each of said insulating sections being tapered in such a manner that when said sections are disposed in substantial axial alignment with an electrical field, the diameter of said bore at the more positive face of each of said sections is greater than the diameter of said bore at the less positive face of the same section.

8. An insulating envelope for supporting at least two bodies at a high potential difference in spaced relationship comprising a pair of closure sections each adapted to support at least one of said bodies, a plurality of plane faced annular insulating sections disposed between said closure sections, said insulating sections being axially aligned and separated by conducting material shims, said shims having their plane faces sealed to adjacent faces of said insulating sections and said closure sections being sealed to the insulating sections adjacent thereto, at least the inner bore of each of said insulating sections being uniformly tapered in such a manner that when said sections are disposed in substantial axial alignment with an electrical field, the diameter of said bore at the more positive face of each of said sections is greater than the diameter of said bore at the less positive face of the same section.

9. An insulating envelope for supporting at least two bodies at a high potential difference in spaced relationship comprising a pair of closure sections each adapted to support at least one of said bodies, a plurality of plane faced annular insulating sections disposed between said closure sections, said insulating sections being axially aligned and separated by conducting material shims, said shims having their plane faces sealed to adjacent faces of said insulating sections and said closure sections being sealed to the insulating sections adjacent thereto, at least the inner bore of each of said insulating sections being uniformly tapered in such a manner that when said sections are disposed in substantial axial alignment with an electrical field, the diameter of said bore at the more positive face of each of said sections is greater than the diameter of said bore at the less positive face of the same section.

10. An insulating envelope for supporting at least two bodies at a high potential difference in spaced relationship comprising a pair of closure sections each adapted to support at least one of said bodies, a plurality of plane faced annular insulating sections disposed between said closure sections, said insulating sections being axially aligned and separated by conducting material shims, said shims having their plane faces sealed to adjacent faces of said insulating sections and said closure sections being sealed to the insulating sections adjacent thereto, at least the inner bore of each of said insulating sections being uniformly tapered in such a manner that when said sections are disposed in substantial axial alignment with an electrical field, the diameter of said bore at the more positive face of each of said sections is greater than the diameter of said bore at the less positive face of the same section.

11. An insulating envelope for supporting at least two bodies at a high potential difference in spaced relationship comprising a pair of closure sections each adapted to support at least one of said bodies, a plurality of plane faced annular insulating sections disposed between said closure sections, said insulating sections being axially aligned and separated by conducting material shims, said shims having their plane faces sealed to adjacent faces of said insulating sections and said closure sections being sealed to the insulating sections adjacent thereto, at least the inner bore of each of said insulating sections being uniformly tapered in such a manner that when said sections are disposed in substantial axial alignment with an electrical field, the diameter of said bore at the more positive face of each of said sections is greater than the diameter of said bore at the less positive face of the same section.
